UNITED STATES PATENT OFFICE

147,809

DESIGN FOR A SALT TABLET DISPENSER

Paul C. Perrin, Pittsburgh, Pa., assignor to Mine Safety Appliances Company, Pittsburgh, Pa., a corporation of Pennsylvania

Application February 18, 1946, Serial No. 126,653

Term of patent 14 years

(Cl. D52—2)

To all whom it may concern:

Be it known that I, Paul C. Perrin, a citizen of the United States, residing at Pittsburgh, in the county of Allegheny and State of Pennsylvania, have invented a new, original, and ornamental Design for a Salt Tablet Dispenser, of which the following is a specification, reference being had to the accompanying drawing forming a part thereof.

Fig. 1 is a front view of the salt tablet dispenser showing my new design; Fig. 2 is a side view thereof; and Fig. 3 is a plan view of the salt tablet dispenser.

I claim:

The ornamental design for a salt tablet dispenser, as shown.

PAUL C. PERRIN.
